M. P. OSBOURN

REFRIGERATING SYSTEM

Filed Aug. 13, 1920

UNITED STATES PATENT OFFICE.

MILLARD P. OSBOURN, OF PHILADELPHIA, PENNSYLVANIA.

REFRIGERATING SYSTEM.

Application filed August 13, 1920. Serial No. 403,331.

To all whom it may concern:

Be it known that I, MILLARD P. OSBOURN, a citizen of the United States, and a resident of the city of Philadelphia, in the county of Philadelphia and State of Pennsylvania, have invented certain new and useful Improvements in Refrigerating Systems, of which the following is a specification, reference being had to the accompanying drawing.

My invention relates to a system of refrigeration based upon the principle of heat extraction by evaporation of a part of the refrigerant by a constantly maintained high vacuum. For the purpose of more clearly illustrating the application thereof, I have herein described, and shown on the accompanying drawing, a few embodiments of my invention in apparatus adapted to carry out the principles of my invention.

One of the objects of this invention is to provide a novel and useful refrigerating system or apparatus of simple construction and of unitary organization.

Another object is to so construct such a system or apparatus whereby the refrigerating effects, temperature depressions or heat abstractions may be accomplished wholly by a comparatively simple and reliable mechanical means without the utilization or the intervention of any chemical or chemical reactions and with the elimination of the complicated and cumbersome devices heretofore found essential to reach similar ends.

One of the principal objects of this invention is to provide a system of refrigeration or a refrigerating apparatus adapted to operate upon the principle or known law of nature that the evaporation of a liquid, such as water or solutions composed mainly of water and a dissolved substance, effects a cooling thereof, if the solution be not supplied with heat from an available source.

Another object is to provide the aforesaid system or apparatus with means, in the attainment of the results incidental to refrigeration, capable of rapidly and efficiently abstracting or absorbing heat from the refrigerant or cooling medium.

A still further object is to provide such system or apparatus with means adapted to produce a high vacuum or very low absolute pressure corresponding to the vapor tension of the liquid or refrigerant at any desired temperature.

Still further objects and advantages are

to provide a system or apparatus which is capable of great capacity; will occupy very little space; be comparatively cheap to construct, involving extremely low first cost of 60 installation; operate very economically with practically no wear and tear and practically automatically when once set in operation; require very little or no attention or attendance; be perfectly safe and free of any danger, as from explosions, requiring no pressure higher than that of the atmosphere; requiring no chemicals, avoiding any recharging and eliminating practically all losses by leakage, corrosion, deterioration and the 70 like; reduce the cost of repairs and maintenance to an inconsequential or negligible quantity; operate at a very small expense of energy or power; do away with the use of steam ejectors or other steam appliances of 75 any kind, condensers, air pumps, circulating pumps, cooling towers, cooling coils, turbines and the like, and operate with an extremely high efficiency.

A still further object is to provide the system or apparatus with means to render non-available any supply of heat from the exterior of the system or apparatus other than from the device or articles upon which the refrigerant or cooling medium imposes its 80 cooling effect, such as a refrigerator containing food and similar goods; such means being preferably in the nature of a vacuum jacket and being so constructed that the vacuum thereof will be self-created and self-sustained from the operation of the system or apparatus.

A still further object is to construct the apparatus for operation at pressure below that of the atmosphere, thereby avoiding the 95 danger of explosions, leakage and the like.

Such other objects and advantages that are present in my invention will more fully appear in the following specification and upon the accompanying drawing.

For the purpose of making clear the law of nature involved, reference is made to the fact that any liquid, when vaporizing, must be supplied with heat, and, if no other source of heat is available, it will be drawn from 100 the liquid itself, which is consequently cooled.

By my system, the substance to be cooled, which may be water, brine or any aqueous solution (calcium chloride may be used instead of salt or sodium chloride), is cooled 110 directly within the apparatus without the

use of a separate cooler, nor of a series of devices for producing a vacuum, such as steam ejectors, condensers and air pumps, and the auxiliaries thereto.

8 My invention therefore is not limited, nor is it intended to be limited, to merely refrigeration, as it is and will be apparent from the herein disclosure.

10 Referring more particularly to the drawings, in which corresponding reference characters are used to designate corresponding elements in the figures shown,

15 Fig. 1 is a vertical transverse section of one form of refrigerating apparatus, constructed in accordance with the invention: and,

Fig. 2 is a similar view of another form.

20 Referring now more particularly to the drawing, the embodiment illustrated in Fig. 1, comprises a double wall casing 1 having a vacuum space 2 between the walls thereof for the purpose of insulating the interior of the casing from the entrance of heat, as will become apparent from the hereinafter disclosure. The casing may be divided into two 25 chambers 3 and 4, by a transverse wall 5, the chamber 3 being in the lower portion of the casing and the chamber 4 being in the upper part thereof. The upper part of the casing 30 may be made detachable with the lower part and secured thereto by means of bolts 6. A cover 7 may be used to substantially close the chamber 4, said cover being provided with an opening or vent 8, for a purpose 35 hereinafter more fully disclosed.

25 In the lower chamber 3 of the device may be located a vacuum pump 9, of any suitable form, such as the type disclosed in my co-pending application, Serial No. 400,174, filed July 30, 1920. This pump may be operated by a motor 10, located outside of the casing 1 and driven by means of a shaft 11, extending into the casing and conveniently connected to the pump. The pump may be 40 provided with liquid inlet ports 12, an inlet conduit 13 and a discharge conduit 14 leading in the upper chamber 4. The inlet conduit 13 to the pump extends upwardly above the normal level of the liquid 15 in the lower 45 chamber and is provided with a fitting 16 having an inlet 17 through which vapors from the upper part of the chamber 3 enter when the pump is operating and creating a vacuum in said chamber above the liquid 50 15. Upon the fitting 16 may be connected an ejector 18, known in the art as the Worthington rotary spray ejector, adapted under the vacuum formed in the fitting 16 to cast a whirl of liquid spray in the fitting 16 and conduit 18, such liquid being fed to said ejector through a pipe 19 connected to the ejector and the upper chamber 4. The pipe leads to a T casing 20 having therein 55 a valve connected to a stem 21 extending through a spray head 22 connected to the

lower side of the fitting or casing 20. The lower end of the stem 21 is provided with a float 23 adapted to move with the liquid level in the lower chamber whereby the valve in the casing 20 may open to permit passage 70 of fluids, such as brine and the like, into the spray head 22 to be sprayed into the chamber 3, when the level of the liquid 15 is low. To the casing 20 is connected a pipe 24 leading through and to the exterior of the casing 1 to a coil 25 which may be located in a refrigerator chamber or similar place where cooling effects are to be produced. The upper end of the coil 25 leads to a control valve 26 and a pipe 27, the latter being connected to the upper chamber 4.

75 The control valve 26 is of utility to regulate and control the flow of the refrigerating fluid, such as brine, from the chamber 4, through the coil 25 to the chamber 3. The means for effecting the valve comprises a thermostat 28 located in the refrigerating chamber, a tube 29 connected to the thermostat and a diaphragm chamber 30, said tube containing any suitable fluid adapted to expand and contract upon rise and fall in temperature. The diaphragm of the chamber 30 may be connected to the valve stem 31 whereby an opening and closing movement of the valve 26 may be effected upon the expansion or contraction of the fluid in the tube 29 and thermostat 28.

80 In the chamber 4 may be located a float 32 connected to a stem 33 pivotally connected or jointed to a bell crank lever 34 pivotally mounted upon the cover 7. An arm 35 of the lever 34 carries an adjustable weight 36 and a pin 37 adapted to operate in a slot 38 provided at the end of the switch arm 39, the latter being connected to a switch 40 controlling the circuit 40' to the motor 10.

85 In operation, the pump 10 operates submerged in the liquid 15 at a high speed of rotation, and creates and maintains a high 90 vacuum in the inlet conduit 13 as well as the chamber 3 above the level of the liquid 15, the vapors and gases being drawn from said chamber through the inlet 17 of the fitting 16. The rotary ejector 18, due to the 95 force of the vacuum in the conduit 13 and fitting 16, causes a spray of liquid to form in said fitting as the vapors are withdrawn from the opening 17. A mixture of liquid and vapors is then drawn into the pump and forced upwardly through the discharge 100 connection 14 into the chamber 4. As the mixture becomes quiet in the chamber 4, the vapors will be disengaged from the liquid and passed upwardly through the perforation or vent 8 in the cover 7, to the atmosphere. This liquid will be of a comparatively low temperature and will circulate by 105 gravity through the pipe 27, coil 25 and pipes 24 and 29, to the ejector 18, a portion 110 of the liquid passing into the spray head and 115

sprayed into the chamber 3, when the float 23 is lowered by the liquid level in the chamber 3. The float 23 operates to open the valve in the fitting 20 to permit the liquid to flow into the spray head 22 and to be sprayed in the form of a fine rain into the vacuum space of the chamber 3 above the liquid 18. Inasmuch as this spray is formed in a vacuum a portion of the liquid thereof will be evaporated into vapor and as evaporation occurs within an insulated chamber, the remaining portion of the liquid will be cooled. The cooled liquid will flow downwardly at the sides of the pump and enter the ports 12 of the pump, thereby operating upon the fluids flowing to the pump from the inlet conduit 18 and rising in the connection 14 to the chamber 4. The cooled liquid in the chamber 4 then flows by gravity into the coil 25 and returns to the ejector and spray head as before. The thermostat, being located in the refrigerator compartment operates, as the temperature rises, to cause an opening of the valve 26 whereby more cooling fluid may circulate through the coil 25, thereby reducing the temperature in the refrigerator compartments. As the circulation of the refrigerating fluid increases, the liquid level in the chamber 4 is lowered and the float 32 will be accordingly lowered. As the arm 35 is drawn past the vertical, the weight 36 will cause it to move rapidly to its limits with the pin 37 operating in the slot of the arm 39 whereby the switch 40 may be quickly thrown; in this case to close the circuit. This will effect a starting of the motor 10 and the pump 9 until the liquid level in the chamber 4 is re-established. As the level rises, the float 32 rises and the arm 35 is again thrown toward the position shown in Fig. 1, whereby the pin 37 will contact at the other end of the slot 38 in the arm 39 and cause the switch 40 to be thrown open.

The form of device shown in Fig. 2 comprises a casing 41 having a single chamber 42, the casing walls being double and provided with vacuum spaces 43 therebetween. A cover 44 may be provided to close the upper end of the chamber 42. Within this chamber is located a vacuum pump 45 of any suitable type, such as shown in my pending application, Serial No. 400,174, filed July 30, 1920, the pump being adapted to operate submerged. The pump may be provided with a pair of vapor or gas intakes 46, leading from the vacuum space above the level of the liquid 47 into the pump chamber, inlet ports 48 for the liquid and a discharge conduit 49 extending to the exterior of the casing 41 at a suitable height. The conduit 49 may have connected thereto a circulating pipe 50 leading from the conduit 49 above the cover 44 to the lower portion of the chamber 42. The pipe 50

may be provided with a valve 51 of any suitable form, the stem 52 of which may be connected to a link 53 jointed to a lever 54 pivotally supported at one end thereof on the bracket 55, the latter being rigidly secured to the conduit 49. To the other end of the lever 54 may be connected a rod 56 which is provided at its lower end with a float 57 adapted to operate in the conduit 49. As the level of the liquid in the conduit 49 rises, the valve is accordingly opened and the liquid is adapted to flow therefrom through the pipe 54 into the bottom of the chamber 41. The upper end of the conduit 49 is open to the atmosphere in order that as the vapors disengage from the liquid therein, the same may pass off into the atmosphere.

A refrigerant circulating pipe 58 provided with a coil 59 is connected to the chamber 41 with the upper end thereof just below the normal level of the liquid 47 therein and the lower end thereof to the lower portion of the casing 41 whereby circulation of the refrigerant may be upwardly through the coil 59 and pipe 58.

A motor 60 adapted to drive a shaft 61 is connected to the pump 45. In both forms shown, the conduits at the outside of the casings 1 and 41 may be heat insulated in any suitable manner, as by covering the same with insulating material.

In operation, the pump 45 operates to create a vacuum in the upper space of the chamber 42, whereby the vapors therein are drawn downwardly into the inlet pipes or vapor intakes 46 into the pump 45. At the same time liquids enter the ports 48 of the pump 45 and operate upon the vapor therein to be ejected therewith through the pipe 49, the pump operating in submerged condition. The mixed liquid and vapors rise into the pipe 49, where the vapors may disengage therefrom and pass to the atmosphere. The liquid may then circulate through the pipe 50 back into the lower portion of the chamber 42. It will be noted that as the vacuum is created and maintained in the upper space of the chamber 42, a certain amount of the liquid 47, at the surface thereof, will be evaporated thereby giving up latent heat of evaporation, whereby the liquid will be cooled. The cooled liquid will descend into the chamber 42 and rise through the pipe 58 and coil 59, the coil 59 being located in a refrigerator compartment or like place where cooling effects are desired, the warm liquid then passing through the pipe 58 into the upper part of the chamber 42.

Having thus described and shown upon the accompanying drawing certain embodiments constructed in accordance with my invention, it is however, to be understood that the invention is not limited to the particu-

lar details and arrangement of parts shown and described, but that the invention comprehends other embodiments, details and arrangement of parts as do not depart from the spirit of the invention and the scope of the appended claims.

Having thus described my invention, what I claim and desire to protect by Letters Patent of the United States is:

1. In a refrigerating system, the combination of a closed chamber containing a refrigerant in the lower portion thereof, a pump submerged in said refrigerant for commingling said refrigerant with the vapors in said chamber above said refrigerant and for continuously expelling said commingled refrigerant and vapor from said closed chamber to produce a partial vacuum in said chamber above said refrigerant, a receptacle into which the discharge from said pump is delivered and from which said vapors escape from said refrigerant, and a conduit from said receptacle to the space in said closed chamber above said refrigerant.

2. In a refrigerating system, the combination of a closed chamber containing a refrigerant in the lower portion thereof and a vacuum space above said refrigerant, vacuum producing means having inlet ports submerged in said refrigerant, said means being provided with an intake leading from said vacuum space and a discharge conduit subject to atmospheric pressure, means for operating said vacuum producing means whereby a high partial vacuum is maintained in said vacuum space by the withdrawal of vapors therefrom through said intake and discharging the same through said discharge conduit whereby said vapor disengages from the fluids of greater density, and means for circulating said refrigerant.

3. In a refrigerating system, the combination of a closed chamber containing a refrigerant in the lower portion thereof and a vacuum in the upper portion thereof, means located in said chamber for creating and maintaining a partial vacuum in said upper portion of said chamber, said means being provided with an intake leading from said vacuum space, and a discharge conduit subject to the pressure of the atmosphere, the partial vacuum in said vacuum space causing an evaporation of a portion of the refrigerant whereby said refrigerant is lowered in temperature, means for circulating said cooled refrigerant, thermostatic means

for controlling the circulation of said refrigerant, and means controlled by the liquid level of said cooled refrigerant for controlling the operation of said vacuum creating means.

4. In a refrigerating system, the combination of means having a closed chamber for containing a liquid refrigerant and a vacuum space above said refrigerant, means for creating and maintaining a partial vacuum in said vacuum space whereby a portion of said refrigerant is evaporated to lower the temperature of said refrigerant, means for circulating the cooled refrigerant, means controlled by the temperature of the air surrounding said circulating means for controlling the rate of circulation of said refrigerant in said circulating means, and a float controlled means for controlling the operation of said vacuum creating means in accordance with the rate of flow of said refrigerant through said circulating means.

5. In a refrigerating system, the combination of means having a closed member for containing a liquid refrigerant and a vacuum space above said refrigerant, means for creating and maintaining a partial vacuum in said vacuum space whereby a portion of said refrigerant is evaporated to lower the temperature of said refrigerant, means for circulating the cooled refrigerant, means controlled by the temperature of the air surrounding said circulating means for controlling the rate of circulation of said refrigerant in said circulating means, a float controlled means for controlling the operation of said vacuum creating means in accordance with the rate of flow of said refrigerant through said circulating means, and float controlled means for diverting a portion of said circulating refrigerant into a spray in said vacuum space.

6. In a refrigerating system, the combination of means having a closed chamber for containing a liquid refrigerant and a vacuum space above said refrigerant, means for creating and maintaining a partial vacuum in said vacuum space whereby a portion of said refrigerant is evaporated to lower the temperature of said refrigerant, means for circulating the cooled refrigerant, and float controlled means for diverting a portion of said circulating refrigerant into a spray in said vacuum space.

In witness whereof, I have hereunto set my hand this 11th day of August, 1920.

MILLARD P. OSBOURN.
